Atty.

UNITED STATES PATENT OFFICE.

GEORGE L. KRABER, OF PORTLAND, OREGON, ASSIGNOR, BY MESNE ASSIGNMENTS,
TO THE TURBINE AIR TOOL COMPANY, OF CLEVELAND, OHIO, A CORPORATION
OF OHIO.

PORTABLE TOOL.

1,366,389.

Specification of Letters Patent. Patented Jan. 25, 1921.

Application filed April 17, 1918. Serial No. 229,138.

To all whom it may concern:

Be it known that I, GEORGE L. KRABER, a citizen of the United States, and a resident of Portland, county of Multnomah, State of Oregon, have invented a certain new and useful Improvement in Portable Tools, of which the following is a specification.

The object of my invention is to render the portable planing tool more efficient for its work; by providing means for regulating the depth of the cut taken.

I attain my object by mounting the planing tool on a support which is adapted to be moved over the surface to be worked, and holds the knives of the planing tool in proper relation with such surface.

In putting my invention into practice I prefer to support the planing tool in a single casting having for the base a rear and forward shoe. The forward shoe slopes upward toward the outer end thereof, allowing for regulating the depth of cut of the knives of the planing tool. This regulation is determined by a runner fastened to the bottom face of the forward shoe and controlled by a thumb screw in the front end of the shoe.

My device also comprehends certain other detailed features of improvement as will be hereinafter more broadly pointed out, including means for controlling the air to the turbine which constitutes the motor, and means for throwing off, or discharging, the shavings from the tool.

I attain these objects of my invention by the construction shown in the accompanying drawings, in which:

Figure 1 is a side elevation, partly in section, of my device;

Fig. 2 is a front elevation, partly in section;

Fig. 3 is a longitudinal section of the rear handle of my device, showing the air intake valve and controlling lever; and

Fig. 4 is a longitudinal section of the intake valve set within the handle.

My invention comprises a rotary cutter-head *a*, cored out and mounted on the shoulders *b* of two similar rotary turbine wheels *c*, one on each side, only one of these wheels appearing in the sectional view of Fig. 2. These wheels are in turn mounted on shoulders *d* in ball bearing seats *e* in the side plates *f*. The chambers *g* are an integral part of the frame *h*, and connect with the

cored-out section *i* (see Fig. 4) thereby forming the passageway for the fluid from the intake to the rotary wheels *c*. The handle *j* is also a part of the frame *h*, and is provided with a valve *k* for regulating the flow of the compressed air to the rotary wheels *c*. The stem of valve *k* is vertically reciprocable in the handle and projects above the same, so that the operator can readily control the valve, as by pressing on such stem with his thumb, without releasing his grasp on the handle.

The frame, or body *h* is made of elongate form so as to have an elongate and sufficient straight line bearing-face.

But at its end *h'* the bearing-face is offset inward from said straight line, and preferably at an angle to the latter, as shown in Fig. 1. The end of the bearing-face so offset is covered by an adjustable shoe-plate *u*, having a rotary movement with the axis of rotation as at *v*, that is close to the point where the knife-element comes into action. The free end of the shoe-plate *u* is curved upward, as at *w*, for the purpose of adapting my planing tool to glide over uneven places in the surface being planed, and also to adapt my planing tool for planing convex and concave surfaces.

The adjustable end of the shoe-plate *u* is provided with a rotatable screw *y* threaded in the body of the frame *h'*, and provided with a lock nut *z*.

The frame *h* cooperates with side plates *f* to substantially completely include the cutter head *a* save at the bottom where the cutter knives are allowed to project through to a depth equal to that of the cut desired to be made. Also at a point above and slightly to the front of the axis of the cutter head, having regard to the direction of movement of the tool when in use, this inclosing portion of the frame is raised clear of the cutter head and left open at one side, so as to form a flaring discharge spout or hood for the chips or shavings. The escaping air from both rotary wheels *c* is obviously compressed and directed in its escape and so produces a sufficient draft to effectively clear the cutter blades of the waste material referred to and discharge same to one side of the tool.

The detailed construction of the cutter head need not be described with greater particu-

larity than above, since such construction forms the subject-matter of a separate pending additional application filed Oct. 7, 1918, Ser. No. 257,255.

5. I claim:

1. In a portable tool of the character described, a body or frame having a bearing-face receding from a straight face at one end, an adjustable straight-face shoe plate 10 overlying said receding straight face of the frame, the outer end of said shoe-plate being curved back over the front end of the frame, and means for adjusting the outer end of the shoe-plate relatively to said straight face of the frame.

2. In a portable tool of the character described, a body or frame having a bearing-face receding from a straight face at one end, an adjustable straight-face shoe plate 20 overlying said receding straight face of the frame, the inner end of said shoe-plate lying in said straight face, the outer end of said shoe-plate being curved back over the front end of the frame, and means for 25 adjusting the outer end of the shoe-plate relatively to said straight face of the frame.

3. In a tool of the character described, an elongate body or frame, having a straight line bearing-face with one end off-set 30 inwardly from said straight line, a shoe-plate covering said off-set end and having an angular adjustment with respect thereto, with the angle of rotation located close to the point where the knife-element comes 35 into action, and means for adjusting the free end of said shoe-plate relatively to the straight face of said body.

4. In a tool of the character described, an elongate body or frame having a straight 40 line bearing-face with one end off-set inwardly at an angle to said straight line, a shoe-plate covering said off-set end and having an angular adjustment with respect thereto, with the angle of rotation located 45 close to the point where the knife-element comes into action, and means for adjusting the free end of said shoe-plate relatively to the straight face of said body.

5. In a tool of the character described, 50 an elongate body or frame having a straight line bearing-face with one end off-set inwardly from said straight line, a shoe-plate covering said off-set end and having an angular adjustment with respect thereto,

with the angle of rotation located close to 55 the point where the knife-element comes into action, and means for adjusting the free end of said shoe-plate relatively to the straight face of said body, the free end of said shoe-plate being curved back.

6. In a tool of the character described, an elongate body or frame having a straight line bearing-face with one end off-set inwardly at an angle to said straight line, a shoe-plate covering said off-set end and having an angular adjustment with respect thereto, with the angle of rotation located close to the point where the knife-element comes into action, and means for adjusting the free end of said shoe-plate relatively 60 to the straight face of said body, the free end of said shoe-plate being curved back.

7. In a tool of the character described, the combination of a suitable frame, a rotary cutter head mounted therein, and a turbine wheel attached to said cutter head for rotating same, said frame inclosing said cutter head and wheel and being formed with a flaring discharge spout, whereby the escaping fluid from said wheel 70 will clear said cutter head of waste material.

8. In a tool of the character described, the combination of a suitable frame, a rotary cutter head mounted therein, and two turbine wheels attached to said cutter head for rotating same, one on each side thereof, said frame inclosing said cutter head and wheels and being formed above with a flaring laterally opening discharge 80 spout, whereby the escaping fluid from said wheel will clear said cutter head of waste material.

9. In a tool of the character described, the combination of a suitable frame, a rotary cutter head mounted therein, a turbine wheel attached to said cutter head for rotating the same, said frame being provided with a handle at one end and with a passageway for the compressed fluid 90 designed to operate said wheel disposed adjacent to said handle, a valve controlling said passageway, and a stem on said valve reciprocable in said handle and extending beyond same so as to be operable by the hand 100 grasping said handle.

GEORGE L. KRAMER.
